United States Patent

Des. 240,691
Patented July 27, 1976

240,691

MOBILE DISPLAY DEVICE

John M. Larkin, 6304 Colby Ave.,
Des Moines, Iowa 50311

Filed Dec. 17, 1974, Ser. No. 533,547

Term of patent 14 years

Int. Cl. D6—04; D20—02

U.S. Cl. D6—181

FIG. 1 is a perspective view of a mobile display device showing my new design;

FIG. 2 is a top plan view thereof;

FIG. 3 is a front elevational view thereof;

FIG. 4 is a side elevational view thereof;

FIG. 5 is a rear elevational view thereof; and

FIG. 6 is a bottom plan view thereof.

All of the vertical interior walls of the box at the upper end of the device are mirrors.

I claim:

The ornamental design for a mobile display device, substantially as shown and described.
